DESIGN FOR A COMBINATION TOOL

Sau Wah Ng, Honolulu, Territory of Hawaii

Application February 4, 1942, Serial No. 105,635

Term of patent 3½ years

To all whom it may concern:

Be it known that I, Sau Wah Ng, a citizen of the United States of America, residing at Honolulu, in the Territory of Hawaii, have invented a new, original, and ornamental Design for a Combination Tool, of which the following is a specification, reference being had to the accompanying drawing, forming part thereof.

Figure 1 is a perspective view of one side of a combination tool showing my new design, and Figure 2 is a similar view of the opposite side of the tool.

I claim:

The ornamental design for a combination tool, as shown.

SAU WAH NG.
